[57] **CLAIM**

The ornamental design for a chair, as shown and de-
scribed.

DESCRIPTION

FIG. 1 is a front perspective view of a chair according
to the invention;

FIG. 2 is a side elevation view thereof;

FIG. 3 is a top view thereof;

FIG. 4 is a rear elevation view thereof; and

FIG. 5 is a front perspective view of an alternative
embodiment of the invention similar in all respects to
the embodiment of FIGS. 1-4, except having partially
round legs as opposed to substantially flat legs.

FIG. 1

FIG. 2

FIG. 3

FIG. 4

FIG. 5
